United States Patent

Des. 240,727
Patented July 27, 1976

240,727

VANITY BASIN

Louis A. Garasi, North Hollywood, and Ronald F. Hayes, Northridge, Calif., assignors to L & M Cultured Marble, Chicago Ridge, Ill.

Filed Mar. 12, 1975, Ser. No. 557,628

Term of patent 14 years

Int. Cl. D23—02

U.S. Cl. D23—58

Fig. 1.

Fig. 2.

Fig. 3.

Fig. 4.

Fig. 5.

FIG. 1 is a top plan view of a vanity basin showing our new design;

FIG. 2 is an elevational view taken from one side thereof, the opposite side being a mirror image of the side shown;

FIG. 3 is a front elevational view thereof;

FIG. 4 is a cross-sectional view taken on line 4—4 of FIG. 3; and

FIG. 5 is a cross-sectional view taken on line 5—5 of FIG. 1.

We claim:

The ornamental design for a vanity basin, substantially as shown and described.
